(57) CLAIM

The ornamental design for a cigar cutter incorporating a bottle opener, as shown and described.

DESCRIPTION

FIG. 1 is a top perspective view of a cigar cutter incorporating a bottle opener;

FIG. 2 is a top plan view thereof;

FIG. 3 is a bottom plan view thereof;

FIG. 4 is a front elevation view thereof;

FIG. 5 is a back elevation view thereof;

FIG. 6 is a left elevation view thereof;

FIG. 7 is a right elevation view thereof; and,

FIG. 8 is an environmental drawing showing the cigar cutter opening a bottle.

The broken lines showing a bottle and bottle cap depict environmental subject matter only and form no part of the claimed design.

1 Claim, 3 Drawing Sheets(56)
